UNITED STATES PATENT OFFICE.

JOHN J. HALLIWELL, OF MOUNT VERNON, NEW YORK, ASSIGNOR TO R. HOE AND CO.,
OF NEW YORK, N. Y., A CORPORATION OF NEW YORK.

FOLDING MECHANISM.

Application filed January 15, 1923. Serial No. 612,582.

To all whom it may concern:

Be it known that I, JOHN J. HALLIWELL, a citizen of the United States, residing at Mount Vernon, county of Westchester, and 5 State of New York, have invented certain new and useful Improvements in Folding Mechanisms, fully described and represented in the following specification and the accompanying drawings, forming a part of the 10 same.

This invention relates to certain improvements in folding mechanisms.

In the high speed rotary folders used in connection with high speed printing machines, difficulty has been experienced in getting the fold on the center line of the product at different folder speeds. These folding cylinders are equipped with sheet taking devices, usually pins, by which the head of 15 the sheet or web is taken. The cylinders are also equipped with a folding or tucking blade which is projected from the cylinder at proper intervals to fold off a sheet in to co-operating folding devices, usually a pair 20 of rolls. As the sheet is advanced it becomes necessary to free the sheet from the pins so as to avoid tearing when the sheet is tucked into the rolls. Between the time 25 the sheet is released and the time the sheet is tucked into the rolls the action of the blade on the sheet at the start of the tuck is apt to cause a slip of the sheet on the cylinders, which results in the sheet being folded on a 30 line off center, this being particularly apt 35 to occur at slow speeds, such as when starting.

It is the especial object of the present invention to produce a folder construction in which this slip of the sheet is prevented between the time the sheet is released by the sheet taking devices on the cylinder and the time the sheet is folded off by the folding blade and co-operating folding devices, the sheet being positively held during this time, 40 so that a fold on the center line or other predetermined line, irrespective of the speed at which the folding cylinder is operating, is produced.

It is a further object of the invention to 45 provide a simple and effective mechanism for accomplishing this, and one which can be readily added to folding mechanisms already constructed.

With these and objects not specifically referred to, the invention consists in certain

novel parts, arrangements, and combinations, a detailed description of which will be given in connection with the accompanying drawings, and the novel features pointed out in the claims hereunto annexed. 60

In these drawings—

Figure 1 is a sectional end view, partly broken away, of a folding cylinder and associated mechanism illustrating one construction for carrying out the invention. 65

Figure 2 is a similar view with the parts in a different position.

Figure 3 is a similar view with the parts in a still different position.

Figure 4 is a side view of the construction shown in Fig. 3, looking in the direction of arrow 4 of that figure. 70

Figure 5 is a partial sectional end view illustrating a modified construction for carrying out the invention. 75

Figure 6 is a similar view showing the parts in a different position.

Figure 7 is a similar view showing the parts in a still different position.

Figure 8 is a detail partial end view showing the cam roll and an operating cam; and 80

Figure 9 is a side view of the construction shown in Fig. 8.

Referring now to these drawings which illustrate preferred embodiments of the invention, the improved folding mechanism has been illustrated as used in connection with a web from which sheets are severed and folded. This web, indicated by the letter W may come from a high speed printing machine not shown. 85

This web is forwarded to the folder by forwarding rolls 1, 2, indicated in Fig. 1. From these rolls the web passes to the folding cylinder and cutting mechanism. In 90 the particular construction shown the folding cylinder 3 co-operates with a cutting cylinder 4 to sever the web into sheets. This cutting cylinder is provided with a cutting knife 5 and the folding cylinder is provided with the cooperating cutting woods 6, the cylinder 4, in the construction shown, being half the diameter of the folding cylinder. 100

The folding cylinder is provided with sheet taking devices which seize the web and advance it. While these sheet taking devices may be of various forms, in the particular construction shown, they are pins 7, two sets of these pins being shown, mounted 105 on lever arms 8 fast on shafts 9 rocked by 110

a cam 10 to project the pins and retract them to release the sheets.

The folding cylinder 3 is also equipped with a folding blade 11 which is mounted 5 on a shaft 12 operated by a cam 13 to project and retract the blade at suitable times. Co-operating with the blade 11 is a folding mechanism operating to fold off a sheet. This mechanism, in the particular construction 10 shown is a pair of rolls 14, 15, preferably driven from the folding cylinder 3 by means of a gear 16 on the shaft 17 of the roll 15, this gear meshing with a gear 18 on the shaft of the folding cylinder, and 15 driving the other roll by engaging a gear 19 on the shaft 20 thereof.

In accordance with the invention, means are provided for preventing the sheet from slipping on the cylinder after it has been 20 released by the pins, the sheet being preferably positively held against the cylinder between the time of its release and the time the blade tucks it into the bite of the folding rolls. Various means may be employed for 25 effecting this and two such means are illustrated in the drawings. Referring first to Figures 1 to 4, there is shown a presser member having a raised portion which engages the sheet at the desired time to press it 30 against the cylinder. While the construction of this presser member may be somewhat varied, as shown it consists of a plurality of spaced rolls 21 mounted on a shaft 22 suitably journaled in side frames 23. 35 Each of the disks 21 has a raised portion 24 on its periphery and the shaft 22 is preferably spring seated as at 25, so that a surface contact between the raised portions of the rolls and the cylinder is ensured. This 40 shaft is driven at the speed of the folding cylinder by means of a gear 26 meshing with a gear 26' on the folding cylinder shaft.

In Fig. 1 the web is shown forwarded by the pins at a point slightly in the rear of 45 where the pins release the sheet, and the raised portions of the disks are about to come into contact with the web. This contact has been made in the position shown in Fig. 2, and the pins having released the sheet 50 the pressure contact prevents the sheet from slipping on the cylinder. In this position the folding blade is about to come into action and the sheet has been severed from the web. In Fig. 3 the folding blade has tucked 55 the sheet into the bite of the folding rolls, and the raised portions of the disks are about to have contact so that the sheet will be free to be drawn off by the rolls. With this construction the sheet is positively held 60 in correct position with respect to the blade and the fold is always made on a predetermined fold line.

In Figs. 5 to 9 a modification is shown for 65 effecting the holding of the sheet against the cylinder at the desired time.

In the structure here shown the presser member is in the form of spaced rolls, or disks 27, one of which is shown having a circular periphery, these disks being mounted on a spring seated shaft 28, similar to 70 the shaft 22, before referred to. On this shaft beyond the end of the folding cylinder is an actuating roll 29 arranged to contact with a cam plate 30 on the end of the folding cylinder, this cam plate having two 75 spaced raised portions 31, 32, as shown in Fig. 8, each of these raised portions having front and rear inclined surfaces 33, 34, and 35, 36. In this construction the roll 29 riding up the incline 33 of the raised portion 31 acts to move the shaft 28 and rolls 27 away from contact with the cylinder 3, so that the leading edge of the web and the pins holding it may pass freely between the rolls and the cylinder. As the sheet 80 advances the roll 29 rides off the raised portion 31 and thus permits the rolls 27 to press the web against the cylinder and hold it from any slipping after the pins have been withdrawn. As the blade tucks the sheet 85 into the folding rolls, the roll 29 rides up the incline 35 of the raised portion 32, and actuates the rolls 27 so as to leave the sheet 90 free to be folded off.

While the invention has been shown and 95 described in its preferred forms, it will be understood that various changes may be made in the specific structures disclosed without departing from the invention.

What I claim is:

1. The combination of a folding cylinder 100 having sheet taking devices and a folding blade, folding devices co-operating therewith to fold off a sheet, and pressure devices acting to hold the sheet and prevent it from slipping on the cylinder between the time the sheet taking devices release the sheet and the time the blade tucks the sheet into the co-operating folding devices.

2. The combination of a folding cylinder 110 having sheet taking devices and a folding blade, folding devices co-operating therewith to fold off a sheet, and rotary pressure devices acting to hold the sheet against the cylinder between the time the sheet taking devices release the sheet and the time the blade tucks the sheet into the co-operating folding devices.

3. The combination of a folding cylinder 120 having sheet taking devices and a folding blade, folding devices co-operating therewith to fold off a sheet, and a presser roll arranged to press the sheet against the cylinder between the time sheet taking devices release the sheet and the time the blade tucks the sheet into the co-operating folding devices.

4. The combination of a folding cylinder 125 having sheet taking devices and a folding blade, folding devices co-operating there- 130

with to fold off a sheet, and means for preventing movement of the sheet relatively to the cylinder between the time the sheet taking devices release the sheet and the time 5 the blade tucks the sheet into the co-operating folding devices.

5. The combination of a folding cylinder having sheet-taking devices and a folding blade, folding devices co-operating therewith to fold off a sheet, a presser roll, and a raised portion on one of the parts operating to cause a pressure between the parts which cause a sheet to be held against the cylinder between the time the sheet-taking 10 devices release the sheet and the time the blade tucks the sheet into the cooperating folding devices.

6. The combination of a folding cylinder having sheet taking pins and a folding 20 blade, a pair of folding rolls into which a sheet is folded off by the blade, and a roll rotating at the cylinder speed and timed to hold the sheet against the cylinder between the time the sheet taking devices release the sheet and the time the blade tucks 25 the sheet into the bite of the rolls.

7. The combination with web forwarding devices, of a folding cylinder having sheet taking devices and a folding blade, a co-operating cutting cylinder, a pair of folding rolls into which a sheet is folded off by the blade, and a roll rotating at cylinder speed and timed to hold a cut sheet 30 against the cylinder between the time the sheet taking devices release the sheet and the time the blade tucks the sheet into the co-operating folding devices.

8. The combination of a folding cylinder having sheet taking devices and a folding

blade, folding devices co-operating therewith to fold off a sheet, and spring seated pressure devices acting to press the sheet against the cylinder after it has been released from the sheet taking devices.

9. The combination of a folding cylinder having sheet taking devices and a folding blade, folding devices co-operating therewith to fold off a sheet, a pressure roll acting to press the sheet against the cylinder after it has been released from the sheet taking devices, and a spring seated shaft for the roll.

10. The combination of a folding cylinder having sheet taking devices and a folding blade, folding devices co-operating therewith to fold off a sheet, a pressure roll adjacent the cylinder, and acting to press the sheet against the cylinder after it has been released from the sheet taking devices, a spring seated shaft for the rolls, 55 and gear connections between the shaft and the cylinder.

11. In a rotary folding mechanism, the combination of a folding cylinder and folding rolls of means for holding a sheet to 60 be folded in contact with the folding cylinder until after the sheet is passed into the nip of the folding rolls.

12. In a rotary folding machine, the combination of a folding cylinder, folding rolls, 70 and a presser roll for holding a sheet to be folded in contact with the cylinder until after the sheet is passed into the nip of the folding rolls.

In testimony whereof, I have hereunto 75 set my hand.

JOHN J. HALLIWELL.
